UNITED STATES PATENT OFFICE.

HOWARD ERNEST ALDRICH, OF MIDDLETOWN, NEW YORK.

SWEATBAND FOR HATS.

Application filed May 11, 1923. Serial No. 638,360.

To all whom it may concern:

Be it known that I, HOWARD E. ALDRICH, a citizen of the United States, and a resident of Middletown, in the county of Orange and State of New York, have invented a new and Improved Sweatband for Hats, of which the following is a full, clear, and exact description.

This invention has relation to head wear and refers particularly to a sweat band which is especially designed for use in connection with men's straw hats.

The principal object of the present invention resides in the provision of a sweat band which affords a yieldable and close fitting head receiving opening in order to render the same more comfortable to the wearer while at the same time closely conforming to the shape of the head in order to prevent accidental displacement and to present a neater appearance when positioned on the head.

Other objects and advantages of the invention reside in the simplicity of construction of the sweat band and its mode of application to the hat and the comparatively low cost of production of the same.

With the above recited and other objects in view, the invention resides in the novel construction set forth in the following specification, particularly pointed out in the appended claims and illustrated in the accompanying drawing, it being understood that the right is reserved to embodiments other than those actually illustrated herein to the full extent indicated by the general meaning of the terms in which the claims are expressed.

In the drawing—

Figure 1 is a bottom plan view of a hat equipped with a sweat band constructed in accordance with the invention.

Fig. 2 is a similar enlarged fragmentary view with parts broken away and shown in section to disclose the underlying structure.

Fig. 3 is an enlarged fragmentary vertical sectional view taken approximately on the line 3—3 of Fig. 1.

Fig. 4 is a fragmentary sectional view of the connection between the band stiffening element.

Fig. 5 is a perspective view of the band stiffening element removed.

Referring to the drawing by characters of reference, 10 designates the crown and 11 the rim of a hat with which the improved

sweat band structure is associated. The sweat band structure includes a strip 12 of leather or other suitable material which is cut in arcuate or curved form, the same having more of a curve than is usually provided. A strip of relatively stiff glazed cloth 13 is bent transversely upon itself along a longitudinal line to provide a bight 14 within which a flexible wire 15 is secured by a line of over-stitching 16. The outer or longer arcuate edge of the strip or leather 12 is then attached to the glazed cloth 13 by a line of stitching 17. The opposite ends of the wire are then bent into substantially oval or band form to fit within the entrance of the head receiving portion of the hat at the juncture of the crown with the rim and a line of stitching 18 is passed through the glazed cloth immediately inside of the wire 15 to produce an inwardly bulged portion 19 in the strip at its point of connection with the glazed cloth; the remainder of the strip from the bulged portion being directed upward to lie in substantially concentric spaced relation to the inside of the crown. The ends of the wire are joined by a ferrule or tube section 20. From this construction and arrangement it will be seen that the sweat band or leather affords a cushion head receiving and engaging element which is sufficiently yieldable to afford comfort to the wearer, while at the same time operating to properly engage with the head and conform to the shape thereof for the purpose of preventing accidental displacement and for further presenting a neat appearance when in place. The construction of the sweat band further operates to facilitate its application to the hat; thereby reducing the cost of assembly. The strip 12 is provided with a line of perforations 21 which operate and serve in the capacity of ventilating openings disposed above the point of engagement of the bulged portion with the head.

The gist of the invention resides in employing a relatively stiff resilient element to which the edge of the leather is secured for forcing the same radially inward to provide a bulged portion at its juncture therewith.

I claim:

1. As a new article of manufacture, a sweat band for hats comprising a strip of semi-flexible material, initially of flat arcuate formation, and a relatively stiff resilient

- element secured to the outer edge of the strip for securing in substantially ring form within the head receiving opening to produce in the strip an annular inwardly projecting bulged head engaging portion substantially at its point of juncture of the sweat band with the hat.
2. As a new article of manufacture, a sweat band for hats comprising a strip of semi-flexible material initially of flat arcuate formation, a relatively stiff strip of material doubled upon itself along a longitudinal line, a resilient element arranged and secured in the bight portion thereof, a connection between the outer edge of the first strip and the latter strip adjacent the bight portion, and means for attaching said latter strip adjacent its bight portion within the head receiving opening to force the first strip inwardly to produce an annular inwardly bulged head engaging portion at its

secured edge, as and for the purpose specified.

3. A sweat band for hats comprising a flat arcuate strip of material in band form, a stiffening strip folded along a longitudinal line and secured adjacent its bight portion to the outer edge of the arcuate strip to provide a tunnel, a resilient wire arranged and secured within the bight portion of the stiffening strip having its opposite ends attached to each other, and a line of stitching extending through the stiffening strip and the hat at the point of juncture of the crown with the rim effecting radial contraction of the first mentioned strip to produce an annular inwardly and vertically bulged yieldable head engaging and gripping portion substantially at the juncture of said first mentioned band with the hat.

HOWARD ERNEST ALDRICH.
